UNITED STATES PATENT OFFICE.

JAMES NAYLOR, OF ARLINGTON, NEW JERSEY.

STEAM-CONDENSER.

1,306,273.

Specification of Letters Patent. Patented June 10, 1919.

Application filed September 22, 1915. Serial No. 52,057.

To all whom it may concern:

Be it known that I, JAMES NAYLOR, a citizen of the United States, residing at Arlington, in the county of Hudson and State of New Jersey, have invented a new and useful Steam-Condenser, of which the following is a specification.

My improvements principally relate to that class of condensers known as "barometric," in which a certain amount of steam and a given quantity of water are brought together in a closed chamber at an elevation, sufficient to prevent water from being forced back into the condenser by the pressure of the atmosphere.

The object is to make a condenser of higher efficiency under the varying conditions of every day work, and also to make it simple in construction, and in operation automatic to a certain degree and to render it safe from overflow.

To attain a better vacuum is the aim of all condenser makers for obvious reasons, and to reach this result I would say briefly that my improvements consist of means whereby the bringing together of the steam and the water is more intimate and better accomplished, the condensing chamber better cooled and kept so, the removal of air and non-condensable gases in the proportion to the water used in the quickest possible manner, and with the least expenditure for power.

It also consists of means to give a freer relief to the atmosphere for the steam before there is any vacuum, which means automatically closes when the water is turned on, and when closed is absolutely air tight; and in the construction of parts so that the whole apparatus as installed shall not be of increased cost.

A relief valve is essential for operation in every condenser installation, but in this instance certain improvements are disclosed only applicable to condensers.

In the accompanying drawings which form a part of this specification Figure 1 is an elevation in part sectional, Fig. 2 a full sized detail, Fig. 3 a horizontal cross-section on line 3-3 of Fig. 1, and Fig. 4 a vertical section of the water and air flow at the point of highest velocity which point is indicated by the line 3-3.

Corresponding letters of reference are used in all the figures.

A is the shell of the condensing chamber,

B is the exhaust steam pipe from an engine or the vapor pipe from an evaporator to the condensing chamber, C is the water supply from any available source and always provided with means for regulation, and D is the discharge pipe from the condenser down to the well-known "hot-well" where it has its open end immersed in water with its surface exposed to the atmosphere and with an overflow at a certain elevation to carry off the water and to keep the open end of the pipe water-sealed.

This constitutes the principle of the so-called "barometric" type of condenser.

In my improvements the condensing chamber is provided with an upper and a lower water belt, E and F respectively, all in the same integral part or casting, the former being connected to the water supply and the latter to the discharge pipe, both also communicating with the condensing chamber.

Both these water belts have a common means for cleaning, consisting of hand holes through the outer shell, both on opposite exteriors and provided with air tight covers as shown at G G.

The upper water belt has its uppermost inner surface *c* conical and extending so to the condensing chamber.

This feature is very important in that it permits every rarefied air bubble to be carried by and without the water flow direct and without any possibility of lodgment to the condensing chamber, and at its very uppermost part where the insulating and packing ring H of rubber or other suitable material terminates the condensing chamber, and to a certain extent prevents the heat of the steam pipe passing thereto.

At this point all around the inner circumference is where the steam and the water meet; this feature is also important for it is seen that all the capacity of the condensing chamber is used, and that a flowing film in an unbroken sheet of water passes over every iota of surface.

The overflow edge is rounded, as is plainly shown in Fig. 2; this is to hold the water to the surface of the metal, and to influence it in spreading over the same, especially when less water would be sufficient to condense and to so economize in its use.

So long as there is a running film of water covering the entire inner surface of the condensing chamber, the oncoming steam in its

due proportion will be condensed and no heat above that of the passing water can be communicated to the metal of the chamber. This is an ideal condition and is perfectly met by the new construction shown.

When the full capacity of the pipe C is required the annular opening becomes the nozzle of the water belt, which directs the water into the condensing chamber on the 10 line c of the conical roof, upward and inward; the increased quantity in the chamber overflows into the lower water-belt F through the opening f.

The water in passing down and out of the 15 condensing chamber carries with it the heat and water from the steam in a perfect union, but not so with the air and all the other non-condensables.

As heretofore stated the condenser chamber and water belts are integral, being cast 20 without the annular openings and the rounded upper edge, the same being machined at the same operation as when the flanged ends are faced, so that all the finished surfaces are true to each other.

Located between the condensing chamber and the discharge is the vena contracta I or the contracted vein, as shown, its use being to give increased speed or velocity to 30 the passing water; a vortex is created, the action of which is to suck in the rarefied air at the center only, and it is quite apparent that with a given head or pressure and a given size of the water vein the velocity must normally always be the same, and its air extraction efficiency also and, therefore, limited. This is the condition existing in apparatus now in use and with increase of steam used, more water would be 40 required to condense the steam, the contracted part of the pipe would not pass the quantity and it would fill up into the chamber, impairing its action immediately, and reaching a dangerous condition.

45 By the improvement as shown, all this trouble and constant fear is avoided, and any excess of water gives a result which is at once of good service, and automatic in its operation proportionately to the amount 50 of water used above normal. The manner in which this excess water is used is by overflowing it into the lower water belt F, the water passing through the annular opening f, which is of sufficient capacity and contour to allow the excess on accumulation to pass through and to be a barrier when the flow is normal.

Secured into the bottom of the said lower belt are four auxiliary discharge pipes, each 60 of which is provided with a contracted vein of smaller size and similar to the vein I to draw down the air, with and by the overflow of water from the said belt.

The upper ends of these pipes are so fixed 65 as to be at different elevations or levels

within the water belt, the lowest being at the bottom inner surface and the highest shown at J.

It is apparent that the main overflow at f into the water belt would seek the lowest 70 level by gravity and again overflow into the lowest pipe until its capacity was reached; further overflow would raise the level of the water in the belt and the next higher pipe would overflow and so on to 75 the highest. For safety, the total capacity of the final overflows and the central discharge equals the water inlet.

All these auxiliary discharges unite into the one discharge pipe as shown, or each 80 may be carried down separately and independently to the hot well. The pressure of the atmosphere will maintain the discharge at a given height due to the vacuum and above this is the head or pressure which 85 gives the water its velocity in the vena contracta; the water naturally takes a spiral flow which creates a vortex, at the center of which the rarefied air and gases are drawn down as indicated by the dotted lines 90 in Fig. 4.

Hence if the main vein of water can maintain a smaller vein of air at its center to remove a given amount of air from the condensing chamber and all the parts under 95 vacuum, it becomes apparent that as the others come into action by the successive overflows, each one gives additional sucking power to remove the air due to excess of steam and of water.

The required conditions for safe and positive operation is a limited water supply, the contracted veins of correct capacity and a correctly fixed level of the overflow from the condensing chamber. The vertical scope 105 of the vortex from its lowest to highest elevations does not exceed a distance through which air is continually drawn without interruption.

While the conditions in the use of steam 110 indoors may be constant the year around, yet the temperature of the water will differ, so that more will be required in summer and less in winter; the summer-time is provided for by the auxiliaries and the winter or 115 minimum conditions by the means for a thinner spreading of the water over the entire surface of the condensing chamber; its efficiency is thus maintained under all or any conditions.

K is the relief valve to the atmosphere, which is shown closed, the dotted lines showing its position when open. This valve is located at the top of the steam pipe; its parts consist of a valve seat L, its surrounding wall M for water-sealing, a threaded hole m for water pipe connection and the fulcrum lugs N, these being integral with the exhaust steam pipe; the center of the lugs and the valve seat are on the same 130

horizontal plane, with the top of the wall a distance above it, so as to hold water for immersing the valve and to throw the valve cover well away from its seat when open.

5 The movable part O may be termed an oscillating valve; it consists of the weighted valve cover at one end with arched connecting arms to the center hub, and an extending lever provided with a stop to limit its movement, and to the end of which is a chain connection for its manipulation at P.

10 The valve cover is held true to its seat by the center pin n upon which it has a free and limited movement; the limit being the 15 valve seat in the one direction, and the stop against the pipe in the other. Rubber packing is used on the valve cover to which it is well secured.

15 While these improvements are in a general way applicable to "barometric" condensers they may also be applied to other type of condensers and, therefore, I do not confine myself entirely to the former.

20 What I claim as new, and desire to secure by Letters Patent is:

25 1. In a steam condenser a condensing chamber provided with a steam inlet pipe and a water inlet pipe, a water belt integral with said chamber having a conical roof 30 extending inward to the line of the said steam pipe and in contact therewith, an annular opening to said chamber, the lower edge of which is rounded and extends to the path of the entering steam; in combination 35 with a contracted vein discharge from the said chamber.

2. In a steam condenser a condensing chamber provided with steam and water in-

lets and a central contracted vein discharge; in combination with means for an annular 40 overflow from the said chamber at a certain elevation above the said contracted vein and means for conducting the said overflow to the said central discharge.

3. In a steam condenser a condensing 45 chamber provided with steam and water inlets, upper and lower water belts, and a central contracted vein discharge; in combination with means for overflow from the said chamber to the lower water belt integral 50 therewith, having a series of auxiliary contracted veins with their upper openings at different elevations within the said water belt and the said auxiliary veins connected to a common discharge.

55 4. In a steam condenser a condensing chamber provided with steam and water inlets, upper and lower water belts, and a central contracted vein discharge; in combination with means for overflow from said 60 chamber to the lower water belt and means therein to give successive and increased overflow on accumulation of water within the said condensing chamber.

65 5. In a steam condenser a vertical condensing chamber provided with an exhaust steam inlet into the top and an annular water inlet contiguous thereto; in combination with means for overflow and discharge from the said chamber and successive dis- 70 charges from the said overflow at different elevations.
